UNITED STATES PATENT OFFICE.

ANDREW JOSEPH SMITH, OF NEW YORK, N. Y., ASSIGNOR TO SARAH R. CRAIG, OF NEW YORK, N. Y.

PRINTING-PRESS.

1,286,132.

Specification of Letters Patent. Patented Nov. 26, 1918.

Application filed August 31, 1918. Serial No. 252,159.

To all whom it may concern:

Be it known that I, ANDREW J. SMITH, a citizen of the United States, and a resident of the city of New York, borough of Manhattan, in the county and State of New York, have invented new and useful Improvements in Printing-Presses, of which the following is a full, clear, and exact description.

10 The object of the invention is to provide certain new and useful improvements in printing presses whereby static electricity incident to the operation of a printing press is dispelled or neutralized and an equal drying of the ink is obtained without danger 15 of igniting the paper. Another object is to provide a gas burner having a supply valve controlled by electromagnetic means controlled by the stopping and starting device 20 of the printing press to turn on the gas supply on starting the printing press and to automatically shut off the gas supply on stopping the printing press.

With these and other objects in view, the 25 invention consists of certain novel features of construction as hereinafter shown and described and then specifically pointed out in the claims.

A practical embodiment of the invention 30 is represented in the accompanying drawings forming a part of this specification, in which similar characters of reference indicate corresponding parts in all the views.

Figure 1 is a side elevation of my improvements as applied to a printing press, parts of which are shown in section;

Fig. 2 is an enlarged plan view of the main parts of the delivery mechanism of the printing press provided with my improvements;

Fig. 3 is an enlarged rear elevation of the gas burner and the means to control the flow of gas therethrough, the shield for the pilot light being shown in section.

45 Fig. 4 is an enlarged side elevation of the valve mechanism and supporting means thereof;

Fig. 5 is an enlarged cross section of the same on the line 5—5 of Fig. 4;

50 Fig. 6 is a plan view of the same with the

valve casing in section; and Fig. 7 is a side elevation of the electro-magnet employed to open the gas valve.

The printing press 10 of any approved construction is driven by an electric motor 55 11 connected by line wires 12 and 13 with a suitable source of electrical energy. An electric switch 14 under the control of an operator is connected with the line wires 12 and 13 to permit the operator to start 60 and stop the motor 11 and consequently the printing press 10. The printing press 10 is provided at its delivery end with a receiving table 20 for receiving the printed sheets and this table 20 supports a pair of 65 tracks 21 on which is mounted to reciprocate a carriage 22 actuated by a lever 23 or other suitable means forming part of the printing press. The carriage 20 includes a finger shaft 24 bearing a plurality of fingers 25 with which are associated sheet stops 26 and stripper stops 27.

In order to dispel or neutralize the static 75 electricity generated by the movement of the sheets through the press, use is made of a tubular gas burner 30 connected by clamps 31 or similar devices with the finger shaft 24 to reciprocate with the carriage 22. A flexible tube 32 connects a suitable source 80 of gas with a coupling 33 arranged on the gas valve 34 connected by a fitting 35 with an air mixer 36 from which leads a pipe 37 to one end of the gas burner 30 to supply the latter with a mixture of air and gas to be burned in jets under the paper for dispelling the static electricity and for drying 85 the ink.

The valve casing 34 is provided with a valve seat 40 (see Fig. 6) normally closed by a valve 41 having a valve stem 42 pressed 90 on by a spring 43 arranged within the valve casing 34. The valve stem 41 extends through a stuffing box 44 to the outside of the valve casing 34, and on the outer end of the valve stem 42 is secured a shifting collar 45 95 engaged by a pin 46 projecting from an arm 47 fulcrumed at 48 on a bracket 49 attached to the fitting 35 to move with the reciprocating carriage 22. A heavy spring 50 is attached at one end to the bracket 49 and at 100

the other end to the pin 46 to aid the spring 43 in holding the valve 41 normally to its seat. On the arm 47 is journaled a pulley 60 around which passes a cord, cable or other flexible connection 61 also passing around a guide pulley 62 journaled on the bracket 49. One end of the flexible connection 61 is attached to a bracket 63 fastened to the rear end of the receiving frame or bed 64, while the other end of the flexible connection 61 is attached to the upper end of an armature lever 65 of an electromagnet 66 having its wires 67 and 68 connected with the line wires 12 and 13 of the electric motor 11. The electromagnet 66 and its armature lever 65 are mounted on a bracket 69 attached to the frame 64. When the motor 11 is not running then the armature lever 65 is in the position in Fig. 7 and the valve 41 is held in closed position by the action of the springs 43 and 50. When the motor 11 is started by correspondingly throwing in the switch 14 then the electromagnet 66 is energized and imparts a swinging motion to the armature lever 60 from the left to the right whereby a pull is exerted on the flexible connection 61 to swing the arm 47 from the left to the right whereby the pin 46 acting on the shifting collar 45 causes the valve 41 to move into open position thus allowing gas to pass to the burner. The gas is ignited by a suitable pilot light 70 connected by a pipe 71 with a tube 72 extending transversely through the valve casing 34 adjacent the coupling 33, as plainly indicated in Fig. 5. The tube 72 is provided with a port 73 controlled by an adjusting screw 74 to regulate the flow of gas passing directly from the casing 34 to the pilot light 70. An annular shield 75 is mounted on the burner 30 at the pilot light 70 to protect the flame of the pilot light from contact with the paper or other inflammable material. When the motor 11 is stopped by correspondingly manipulating the switch 14 then the electromagnet 66 becomes deenergized and the valve 41 now moves immediately into closed position by the action of the springs 43 and 50, thus shutting off the gas supply from the burner 30. The oscillating movement of the arm 47 is limited by stops 80 and 81 attached to the bracket 49 and extending at opposite sides of the pin 46, as plainly indicated in Figs. 2 and 6.

It is understood that when the printing press is running and the carriage 22 reciprocates then the armature lever 65 is held attracted by its electromagnet 66 to hold the valve 41 in open position, it being understood that the looping of the flexible connection 61 around the pulleys 60 and 62 permits the carriage to reciprocate freely irrespective of the length of the flexible connection 61 incident to the movement of the armature lever 65.

Having thus described my invention, I claim as new and desire to secure by Letters Patent:—

1. In a printing press, the combination of an electric motor for running the printing press and provided with an electric switch to stop and start the motor, a heating means adjacent the path of the paper passing through the press, and electromagnetic means controlled by the said switch and controlling the said heating means to automatically start the heating means on starting the motor and to automatically stop the heating means on stopping the motor. 75

2. In a printing press, the combination of an electric motor for running the printing press and having an electric switch for starting and stopping the motor, a delivery carriage, a burner mounted on the said carriage and provided with a gas supply valve and with a pilot light, and electromagnetic means controlled by the said switch and connected with the said gas supply valve. 80

3. In a printing press, the combination of an electric motor for running the printing press and provided with a switch, a burner provided with a pilot light, means to supply fuel to the burner, a valve controlling the flow of the fuel to the burner, and electromagnetic means controlled by the said switch and connected with the said valve to open the latter on starting the said motor and to close the valve on stopping the motor. 90

4. In a printing press, the combination of an electric motor for running the printing press and provided with an electric switch to stop and start the motor, a reciprocating delivery carriage, a gas burner mounted on the said carriage and provided with a pilot light, a gas valve controlling the flow of gas to the said burner, an electromagnet provided with an armature lever, and connecting means connecting the said armature lever with the said gas valve. 100

5. In a printing press, the combination of an electric motor for running the printing press and provided with an electric switch to stop and start the motor, a reciprocating delivery carriage, a gas burner mounted on the said carriage and provided with a pilot light, a gas valve controlling the flow of gas to the said burner and provided with a valve stem, a shifting collar on the said valve stem, an arm pivoted on the said carriage and provided with a pin engaging the said collar, a pulley on the said arm, a pulley on the said carriage, and a flexible connection secured at one end to the said armature lever and fixed at the other end, the said connection passing around the said pulleys. 110

6. In a printing press, the combination of an electric motor for running the printing press and provided with an electric switch to stop and start the motor, a reciprocating delivery carriage, a gas burner mounted on 130

the said carriage and provided with a pilot light, a gas valve controlling the flow of gas to the said burner and provided with a valve stem, a shifting collar on the said valve stem, an arm pivoted on the said carriage and provided with a pin engaging the said collar, a pulley on the said arm, a pulley on the said carriage, a flexible connection secured at one end to the said armature lever and fixed at the other end, the said flexible connection passing around the said pulleys, and a spring for closing the said valve.

ANDREW JOSEPH SMITH.
